UNITED STATES PATENT OFFICE.

SYDNEY I. PRESCOTT, OF BROOKLYN, NEW YORK, ASSIGNOR TO MOTORFLEX EQUIPMENT COMPANY, OF NEW YORK, N. Y., A CORPORATION OF NEW YORK.

GAS-ENGINE.

1,114,034.

Specification of Letters Patent.

Patented Oct. 20, 1914.

Application filed April 13, 1912. Serial No. 690,553.

To all whom it may concern:

Be it known that I, SYDNEY I. PRESCOTT, a citizen of the United States, residing at Brooklyn, county of Kings, and State of New York, have invented a new and useful Improvement in Gas-Engines, of which the following is a specification.

This invention relates to an improvement in gas engines, particularly those of the two-
10 cycle three-port type.

One of the defects in gas engines of this type is due to the fact that all the burnt gas does not leave the cylinder at the end of the explosion stroke, or a part of the incoming
15 fresh gas follows the burnt gas out of the cylinder and is wasted.

It is one of the objects of the present invention to produce an engine of this type in which efficiency is increased over what has
20 been heretofore possible; first, by opening the ports more quickly; second, by producing an outflowing blast of air in the exhaust conduit to increase the velocity of the exhaust, this blast stopping and a curtain of
25 air being formed adjacent the exhaust port to prevent fresh gas from flowing through the cylinder to the exhaust conduit.

A further defect in engines of this type heretofore known is due to the fact that
30 they are not balanced unless a plurality of cylinders is used, and are not perfectly balanced even then. It is often desirable to use a single cylinder engine, and the efficiency of such engines, when unbalanced, is
35 too low for economical operation.

Another object of the present invention is the production of a compact engine which is in perfect balance, whether a single cylinder or a plurality of cylinders is used, there-
40 by increasing the efficiency over what has been heretofore possible in a similar type of engine, and further providing an engine adapted to run not only at low speed but also at speeds materially higher than is safe
45 in an unbalanced engine.

Another serious defect of engines of this type heretofore known is due to the imperfect cooling of the cylinder or cylinders, whether water or air is used for this pur-
50 pose. When water is used and circulated around the cylinders by a pump, in automobile engines for instance, it soon becomes warm, even reaching the steaming point in many cases. In such engines, the cooling apparatus for the cylinder or cylinders is far from effective. In the operation of many

of the air cooled engines, a blast of air is driven against one side of the cylinder, and this is obviously imperfect as a cooling agent, because it does not equally cool all
50 parts of the cylinder.

It is another object of the present invention to provide a simple air cooling apparatus which does or may include a part of the engine itself, and in which cold air is
55 caused to surround the cylinder or cylinders where the heat is generated and is then driven out to the atmosphere at high velocity, fresh cold air being sent through the air jacket surrounding the cylinder at every
70 explosion.

With these main objects, and other objects not specifically mentioned in view, the invention consists in certain constructions and combinations which will be hereinafter
75 fully described and then specifically set forth in the claims hereunto appended.

In the accompanying drawings, which form a part of this specification and in which like characters of reference indicate
80 the same or like parts, Figure 1 is a longitudinal sectional view of a device constructed in accordance with the invention, Fig. 2 is a longitudinal sectional view of the structure shown in Fig. 1, the section being
85 taken at right angles to the section in Fig. 1, Figs. 3, 4, and 7 are respectively cross-sectional views taken on the lines 3—3,
4—4, and 7—7 in Fig. 1, Fig. 5 is a sectional view similar to Fig. 1, but showing the pistons at the other end of the stroke, Fig. 6 is a longitudinal sectional view of a modification of the cylinder casting and cap shown in Fig. 1, said modification being for the purpose of illustrating the method of applying a water jacket to the cylinder, and Fig. 8 is a cross sectional view taken on the line 8—8 in Fig. 6.

The device selected to illustrate the invention is a single-cylinder engine of the two-cycle three-port type, and it is to be understood that this particular engine is merely one of many possible concrete embodiments of the invention, and that the elements of the various combinations claimed
105 may vary in construction within wide limits.

As shown, there is provided a cylinder casting having an inner wall 1 forming an open end cylinder, and also having an outer wall 2 spaced from the cylinder 1. This casting
110 is further provided with a partition

3 between the inner and outer walls of the casting, this partition being arranged to form a cooling chamber 4 surrounding one end of the cylinder. Mounted within the cylinder 1 is a pair of concentric power pistons of the trunk type, the outer piston being marked 5, and the inner piston being marked 6. There is always a space between the heads of the two pistons and into this space gas is introduced, compressed and ignited, by means to be herein-after described. This space therefore forms what may be termed an explosion chamber, marked 7, within the cylinder. It may be here remarked that the cylinder 1 does not perform the usual function of a gas engine cylinder, for the reason that the charge of gas is exploded between the pistons and there is no strain on the cylinder wall due to the explosion of the gas. In other words, the cylinder acts mainly as a guide or support for the pistons. When a charge of gas is exploded between the pistons, the piston heads travel in straight lines away from each other at equal speed, and then are caused to return to their initial positions. This reciprocating motion is controlled by the following mechanism: There is provided a crank shaft 8 having oppositely disposed cranks 9 and 10—10. This crank shaft is mounted in suitable bearings 11 carried by a casting 12, spaced from the cylinder casting by a hollow block 13. A rod 14 connects the crank 9 with a pin 15 journaled inside the inner piston before referred to. The outer piston 5 is provided with a pair of outwardly projecting bosses 16 located near its lower end and diametrically opposite, and these bosses are connected with the cranks 10—10 by means of rods 17—17, as clearly shown in Fig. 2. The bosses 16 reciprocate within oppositely disposed slots 51 cut in the cylinder wall. It is to be understood that the weight of the inner piston 1 with its connecting rod 14 is equal to the weight of the outer piston 5 with its connecting rods 17—17. It will be therefore readily understood that, in the operation of the device, equal weights are always traveling in opposite directions at equal speed, that this results in perfect balance of the parts and engine as a whole, and that the engine, being in perfect balance, can be run at high speed if desired, and will run smoothly and quietly at all speeds. It will be further observed that the connections between the pistons and crank shaft are direct, and completely housed within the outer wall of the cylinder casting.

60 Located in the wall of the cylinder 1, below the cooling chamber, is what may be termed an inlet chamber 18. This chamber is open to the interior of the cylinder through a port 19. The inlet chamber 18 is further open to the outside of the outer wall

2 of the cylinder casting through the port 20, and it is to be understood that a carburetor, or a conduit leading from any other suitable source of gas supply, may be mounted at the port 20 just described. It is obvious than any suitable carburetor may be used in connection with the device, and therefore none is shown.

The space within the casting 12 and block 13 forms a crank chamber 21, and in this crank chamber the gas coming from the carburetor or other suitable source of supply is slightly compressed in the usual manner before it goes to the explosion chamber. Normally, however, the crank chamber is cut off from the inlet chamber by the walls of the two pistons. The piston 5 is provided with an inlet port 22, and the piston 6 is provided with an inlet port 23, these two ports being adapted to come into register with each other and with the inlet port 19 only at one end of the piston stroke; that is to say, when the piston heads are closest together, as shown in Fig. 1. When these inlet ports are in register, gas flows into the interior of the inner piston and the crank chamber to which it is open.

After gas has been drawn into the crank chamber and therein compressed, it is transferred to the explosion chamber 7. To accomplish this end, there is provided an intake chamber 24, which is open to the crank chamber and which extends more than half way around the cylinder below the partition 3 before referred to. It is of course obvious that when gas is compressed in the gas chamber, it is also compressed in this intake chamber. The piston 5 is provided with a pair of intake ports 25 in its wall, these ports being diametrically opposed and being circumferentially spaced ninety degrees from the inlet ports 19, 22, and 23. The intake ports 25 are always open to the intake chamber 24, irrespective of the position of the pistons. During the greater part of the stroke of the pistons, however, these intake ports are closed by the wall of the inner piston 6. This inner piston is provided, at a point just above its head, with intake ports 26, these ports being formed by walls 27 projecting upwardly from the piston head and forming deflectors which operate, when the ports 26 and the ports 25 come into register with the intake chamber 24, to turn the two streams of gas flowing into the explosion chamber upward along the wall of the chamber toward the head of the outer piston 5 for the well known purpose of following the burnt gas toward the exhaust port. The ports 25 and 26 come into register with the intake chamber 24 when the piston heads are farthest apart, or in the position shown in Fig. 5, after which the gas flowing from the crank

chamber into the explosion chamber is compressed by the approaching movement of the piston heads.

For the purpose of igniting the compressed charge in the explosion chamber, when the pistons are in the position shown in Figs. 1 or 2, or adjacent thereto, there is provided in the wall of the cylinder casting what may be termed an ignition chamber. This ignition chamber, marked 28, is adapted to receive any suitable spark plug or other igniting device not shown but which may be held therein by any suitable and well known means. This igniting device will not project inside the cylinder, but the ignition chamber 28 is open to the interior of the cylinder through the ignition port 29 formed in the cylinder wall. The outer piston 5 is provided with what may be termed an ignition port 30, and the inner piston 6 is provided with an ignition port 31, these piston ignition ports being adapted to come into register with the ignition chamber only when the piston heads are close together. The piston 5 is further provided with piston rings 50 located on either side of its ignition port 30. It will readily be understood that this construction will absolutely prevent the firing of a charge at any time other than the proper time. In the position shown in Figs. 1 and 2, the crank shaft connections are on a dead center. The ignition ports 30 and 31 are large enough to permit the cranks to move slightly off the dead center in either direction without closing the explosion chamber 7 to the ignition chamber 28. This allows for a slight advance or retardation of the igniting device and it is obvious that when the device is timed to ignite the charge when the cranks are slightly off center in one direction, the crank shaft will rotate in one direction, and that when the device is timed to ignite the charge when the cranks are slightly off dead center in the other direction the crank shaft will rotate in the opposite directions.

A detailed description of the particular mechanism by means of which the ignition is effected is unnecessary to a full understanding of the present invention, and it is therefore neither illustrated nor described herein. Any suitably timed ignition mechanism may be used for this purpose.

After the charge in the explosion chamber is ignited and the pistons have moved apart under equal pressure and at equal speeds to the end of the expansion stroke, it is necessary to remove the burnt gas from the chamber. To accomplish this result, there is provided an exhaust port 32 in the wall of the cylinder at the side opposite the ignition chamber 28 and the inlet chamber 18. This exhaust port is normally closed to the explosion chamber 7. The outer pis-

ton 5, however, is provided with an exhaust port 33, and the inner piston 6 is provided with an exhaust port 34. These piston exhaust ports are adapted to come into register with the cylinder exhaust port 32 just before the intake ports 25 and 26 come into register with the intake chamber 24. This is for the purpose of starting the burnt gas out of the explosion chamber before the fresh gas flows in. Located in the outer wall 2 of the cylinder casting, directly opposite the cylinder exhaust port 32, is an exhaust conduit 35 leading to a suitable exhaust pipe, or manifold where more than one cylinder is used. This exhaust port, or manifold may be of any suitable construction and is not herein shown and described because it is not necessary for a full understanding of the present invention. It will be understood that the fresh gas flowing in through the intake ports will displace the outgoing burnt gas in the explosion chamber in a manner similar to that existing in any two-cycle engine, and it will be recognized that since the piston ports approach each other at equal speed, said ports are opened quicker than the ports in an ordinary two-cycle engine. This of course results in getting the burnt gas out of the explosion chamber quicker than has been heretofore possible.

For the purpose of further aiding the outflow of burnt gas and inflow of fresh gas, means are provided for producing a blast of air through the exhaust conduit 35 before the piston exhaust ports open to the cylinder exhaust port 32 and the conduit 35, and this means may vary within wide limits. As shown, however, the exhaust conduit 35 is always open to the cooling chamber 4, but is only intermittently open to the explosion chamber 7. When the piston 5 travels upward, after the ignition of the charge in the chamber 7, the air in the cylinder 1 above the head of the piston 5 is forced into the cooling chamber 4 and blows out through the exhaust conduit 35. This results in eliminating entirely the resistance of the atmosphere to the outflow of the burnt gas, and further results in increasing the velocity of the outflow. Moreover, the velocity of the air forced through the cooling chamber decreases the temperature around and within the cylinder, and this permits of a higher degree of gas compression which increases the power delivered without danger of premature explosion due to high temperature of the cylinder and piston as well as to the high temperature of compression. When the piston 5 reaches its uppermost position, this blast of air is automatically stopped, so that it is not in action when the inflowing fresh gas has filled the explosion chamber. The upper end of the cylinder casting is closed by a cap 36 which is spaced

from the upper end of the cylinder 1 to permit a free flow of air from the interior of the cylinder to the cooling chamber. This cap carries a flexible disk valve 37 the movement of which is limited by a curved plate 38 secured to the cap 36 by means of a rivet 39 or other suitable fastening device.

By an inspection of Fig. 3 it will be seen that a series of air ports 40 are provided which afford communication between the upper and lower part of the cap 36. For the purpose of preventing dust or other solid matter from passing through the air ports 40, the cap 36 is provided with an air strainer 41 of fine wire mesh suitably secured to the upper part of the cap. On the return stroke of the piston 5; that is to say, from the position shown in Fig. 5 to the position shown in Fig. 1, a partial vacuum is produced in the upper part of the cylinder 1. This results in flexing the valve 37 and opening the air ports 40 through which air flows to fill the upper part of the cylinder. Although the air jacket is always open to the exhaust port 35, the downwardly moving piston 5 does not draw burnt gas back from the exhaust pipe to the cooling chamber because the momentum due to the high velocity of the outgoing gas constitutes a resistance to its travel in the opposite direction; that is, back to the cooling chamber, which resistance is far in excess of the very slight resistance of the readily flexible valve 37, especially since the outgoing gas rushing through the exhaust pipe after the blowing action has ceased sets up in the cooling chamber an ejecting action which in itself tends to open the valve 37. It will be readily understood, therefore, that during each reciprocation of the piston, cold air is drawn into the cylinder and is forced through the air jacket or cooling chamber 4. Since the cooling chamber surrounds the expansion chamber even when the pistons are farthest apart, and since the cylinder itself is not subject of direct heat, it follows that a lower degree of temperature will be maintained than has been heretofore possible.

It will be readily understood that the construction just described constitutes an air pump performing two distinct functions; first, to cool the engine, and second, to aid the exhaust. Furthermore, it is apparent that the greater the speed of the motor, the greater speed of the pump will be, and the more cold air will be driven through the cooling chamber.

It is apparent that since the effective area of the two pistons is equal, and since the weight of the two pistons with their respective connections is also equal, the downward thrust on the crank 9 will equal the upward thrust on the cranks 10-10. This results in materially reducing the pressure upon the

bearings 11, and thereby reduces the wear upon said bearings.

It is believed to be unnecessary to use a water jacket for cooling purposes in any engine of this type. If, however, a water jacket is desired, the only change necessary is in the form of the cylinder casting and cap for the same. Referring particularly to Figs. 6 and 8, the cylinder casting is provided with a partition 42, which separates the space between the cylinder 1 and the outer wall 2 into a cooling chamber 43 nearly surrounding the upper end of the cylinder, and further forming a well 44 down one side of the cylinder. The casting is further provided with bosses 45 and 46 to which water circulating pipes may be secured. The casting is further provided with vertical walls 47, 47, which with a portion of the cylinder 1 and outer wall 2 form a channel 48 extending from the space above the top of the cylinder to the exhaust conduit 35. A cap 49 is provided and shaped to close the upper end of the cooling chamber 43, but which keeps the interior of the cylinder in open communication with the air channel 48.

In view of the foregoing, a detailed description of the operation of the device is deemed unnecessary and is therefore omitted in the interest of brevity.

Changes and variations may be made in the structure by means of which the invention is carried into effect. The invention, therefore, is not to be restricted to the precise details of the structure shown and described. Furthermore, certain parts of the invention are capable of use independent of other parts, and such independent use is contemplated.

What is claimed is:

1. In a gas engine, the combination with a support, of a pair of power pistons concentrically mounted in the support, a crank shaft, operating connections between the pistons and crank shaft, an exhaust conduit intermittently open to the space between the pistons, and means coöperating with the conduit for producing a blast of air through said conduit to the atmosphere during the power stroke.

2. In a gas engine, the combination with a support, of a pair of power pistons concentrically mounted in the support, a crank shaft, operating connections between the pistons and crank shaft, an exhaust conduit intermittently open to the space between the pistons, and intermittently operating means coöperating with the conduit for producing a blast of air through the conduit to the atmosphere before the conduit opens during the power stroke, said means being timed to go out of action before the conduit closes to the space between the pistons.

3. In a gas engine, the combination with a support, of a pair of power pistons concen-

- trically mounted in the support, a crank shaft, operating connections between the pistons and crank shaft, an exhaust conduit intermittently open to the space between the 5 pistons, and means coöperating with the conduit for producing a blast of air through said conduit to the atmosphere before the conduit opens, said means including one of the power pistons operating as an air piston.
- 10 4. In a gas engine, the combination with a cylinder, of a pair of power pistons concentrically mounted within the cylinder, a crank shaft, operating connections between the pistons and crank shaft, an exhaust conduit intermittently open to the space between the 15 pistons, and means coöperating with the conduit for producing a blast of air through said conduit to the atmosphere during the power stroke.
- 15 5. In a gas engine, the combination with a cylinder having an ignition chamber in its wall, of a pair of power pistons concentrically mounted within the cylinder and each having an ignition port in its wall 20 adapted to open the space between the pistons to the ignition chamber, a crank shaft, operating connections between the pistons and crank shaft, an exhaust conduit intermittently open to the space between the 25 pistons, and means coöperating with the conduit for producing a blast of air through said conduit to the atmosphere during the power stroke.
- 30 6. In a gas engine, the combination with a cylinder having an ignition chamber in its wall, of an inner and an outer piston concentrically mounted within the cylinder each having an ignition port in its wall 35 adapted to open the space between the pistons to the ignition chamber, piston rings carried by the outer piston on both sides of its ignition port, a crank shaft, operating connections between the pistons and crank shaft, an exhaust conduit intermittently open to the space between the 40 pistons, and means coöperating with the conduit for producing a blast of air through said conduit to the atmosphere during the power stroke.
- 45 7. In a gas engine, the combination with a cylinder having an ignition chamber in its wall, of a pair of power pistons concentrically mounted within the cylinder each having an ignition port in its wall adapted to open the space between the pistons to the 50 ignition chamber, said ports being timed to register with the ignition chamber only at one end of the piston stroke, a crank shaft, operating connections between the pistons and crank shaft, an exhaust conduit intermittently open to the space between the pistons, and means coöperating with the conduit for producing a blast of air through said conduit to the atmosphere during the power stroke.
- 55 8. In a gas engine, the combination with a cylinder having an intake chamber in its wall, of a pair of power pistons concentrically mounted within the cylinder each having an intake port in its wall adapted to open the space between the pistons to the 55 intake chamber, a crank shaft, operating connections between the pistons and crank shaft, an exhaust conduit intermittently open to the space between the pistons, and means coöperating with the conduit for producing a blast of air through said conduit to the atmosphere during the power stroke.
- 60 9. In a gas engine, the combination with a cylinder having an intake chamber in its wall, of a pair of power pistons concentrically mounted within the cylinder each having an intake port in its wall adapted to open the space between the pistons to the intake chamber, said ports being timed to register with the intake chamber only at one 65 end of the piston stroke, a crank shaft, operating connections between the pistons and crank shaft, an exhaust conduit intermittently open to the space between the pistons, and means coöperating with the conduit for producing a blast of air through said conduit to the atmosphere during the power stroke.
- 65 10. In a gas engine, the combination with a cylinder having an exhaust port in its wall, of a pair of power pistons concentrically mounted within the cylinder each having an exhaust port in its wall adapted to open the space between the pistons to the cylinder exhaust port, a crank shaft, operating connections between the pistons and crank shaft, an exhaust conduit intermittently open through the cylinder exhaust port to the space between the pistons, and means coöperating with the conduit for producing a 70 blast of air through said conduit to the atmosphere during the power stroke.
- 70 11. In a gas engine, the combination with a cylinder having an exhaust port in its wall, of a pair of power pistons concentrically mounted within the cylinder each having an exhaust port in its wall adapted to open the space between the pistons to the cylinder exhaust port, said ports being timed to register with the cylinder exhaust port before the 75 pistons reach the end of their expansion stroke, a crank shaft, operating connections between the pistons and crank shaft, an exhaust conduit intermittently open to the space between the pistons, and means coöperating with the conduit for producing a 80 blast of air through said conduit to the atmosphere before the conduit opens.
- 75 12. In a gas engine, the combination with a crank chamber, of a cylinder having a gas inlet chamber in its wall, a pair of power pistons concentrically mounted within the cylinder each having a gas inlet port in its wall adapted to open the inlet chamber to the crank chamber, means for transferring 85

gas from the crank chamber to the space between the pistons, a crank shaft, operating connections between the pistons and crank shaft, an exhaust conduit intermittently open to the space between the pistons, and means coöperating with the conduit for producing a blast of air through said conduit to the atmosphere before the conduit opens.

13. In a gas engine, the combination with a crank chamber, of a cylinder having a gas inlet chamber in its wall, a pair of power pistons concentrically mounted within the cylinder each having a gas inlet port in its wall adapted to open the inlet chamber to the crank chamber said ports being timed to register with the gas inlet chamber only at one end of the piston stroke, means for transferring gas from the crank chamber to the space between the pistons, a crank shaft, operating connections between the pistons and crank shaft, an exhaust conduit intermittently open to the space between the pistons, and means coöperating with the conduit for producing a blast of air through said conduit to the atmosphere before the conduit opens.

14. In a gas engine, the combination with a crank chamber, of a cylinder having a gas inlet chamber and an intake chamber and an exhaust port and an ignition chamber in its wall, a pair of power pistons concentrically mounted within the cylinder each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted to open the ignition chamber to the space between the pistons, a crank shaft, operating connections between the pistons and crank shaft, an exhaust conduit open to the exhaust port of the cylinder, and means coöperating with the conduit for producing a blast of air through said conduit to the atmosphere before the piston exhaust ports open to the cylinder exhaust port and the conduit.

15. In a gas engine, the combination with a crank chamber, of a cylinder having a gas inlet chamber and an intake chamber and an exhaust port and an ignition chamber in its wall, a pair of power pistons concentrically mounted within the cylinder each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted to open the ignition

chamber to the space between the pistons, said gas inlet ports and said ignition ports being timed to register only when the piston heads are closest together and said intake ports being timed to register only when the piston heads are farthest apart and said exhaust ports being timed to register just before the intake ports register, a crank shaft, operating connections between the pistons and crank shaft, an exhaust conduit open to the exhaust port of the cylinder, and means coöperating with the conduit for producing a blast of air through said conduit to the atmosphere before the piston exhaust ports open to the cylinder exhaust port and the conduit.

16. In a gas engine, the combination with a crank chamber, of a cylinder having a gas inlet chamber and an ignition chamber in one side of its wall and an exhaust port in the opposite side of its wall and a pair of intake chambers one at either side of the cylinder both positioned ninety degrees from the exhaust port and open to the crank chamber, a pair of power pistons concentrically mounted within the cylinder each having an inlet port in its wall adapted to open the inlet chamber to the crank chamber and each having a pair of intake ports in its wall adapted to open the intake chambers to the space between the pistons and each having an exhaust port in its wall adapted to open the space between the pistons to the cylinder exhaust port and each having an ignition port in its wall adapted to open the ignition chamber to the space between the pistons, a crank shaft, and operating connections between the piston and crank shaft.

17. In a gas engine, the combination with a crank chamber, of a cylinder having a gas inlet chamber and an ignition chamber in one side of its wall and an exhaust port in the opposite side of its wall and a pair of intake chambers one at either side of the cylinder and both positioned ninety degrees from the exhaust port, a pair of power pistons concentrically mounted within the cylinder each having an inlet port in its wall adapted to open the inlet chamber to the crank chamber and each having a pair of intake ports in its wall adapted to open the intake chambers to the space between the pistons and each having an exhaust port in its wall adapted to open the space between the pistons to the cylinder exhaust port and each having an ignition port in its wall adapted to open the ignition chamber to the space between the pistons, a crank shaft, operating connections between the pistons and crank shaft, an exhaust conduit intermittently open through the cylinder and piston exhaust ports to the space between the pistons, and means coöperating with the conduit for producing a blast of air through said conduit to the atmosphere before the

- piston and cylinder exhaust ports open to the conduit.
18. In a gas engine, the combination with an explosion chamber, of an intake chamber intermittently open to the explosion chamber, an exhaust conduit intermittently open to the explosion chamber slightly ahead of the intake chamber, and means coöperating with the conduit for producing a blast of air through said conduit to the atmosphere during the power stroke.
19. In a gas engine, the combination with an explosion chamber, of an exhaust conduit intermittently open to the chamber, and intermittently operating means coöperating with the conduit for producing a blast of air through said conduit to the atmosphere, said means being timed to come into operation during the power stroke only and before the conduit opens to the chamber and to stop before the conduit closes to the chamber.
20. In a gas engine, the combination with an open end cylinder, of an explosion chamber within the cylinder, an exhaust conduit intermittently open to the chamber, and an air pump including the open end of the cylinder and a reciprocating piston within the cylinder and a flexible disk air inlet valve located adjacent the end of the cylinder, said pump coöperating with the conduit for producing a blast of air through said conduit to the atmosphere before the conduit opens.
21. In a gas engine, the combination with an open end cylinder, of an explosion chamber within the cylinder, an exhaust conduit intermittently open to the chamber, and an air pump including the open end of the cylinder and a reciprocating piston within the cylinder and a flexible disk air inlet valve located adjacent the end of the cylinder and an air jacket inclosing one end of the cylinder, said pump coöperating with the conduit for producing a blast of air through said conduit to the atmosphere before the conduit opens.
22. In a gas engine, the combination with an open end cylinder, of an explosion chamber within the cylinder, an exhaust conduit intermittently open to the chamber, and an air pump including a reciprocating power piston one side of which acts as an air piston within the open end of the cylinder and a flexible disk air inlet valve located adjacent the end of the cylinder and an air jacket inclosing one end of the cylinder, said pump coöperating with the conduit for producing a blast of air through said conduit to the atmosphere before the conduit opens.
23. In a gas engine, the combination with an open end cylinder, of an explosion chamber within the cylinder, an exhaust conduit intermittently open to the chamber, and an air pump including a reciprocating power piston one side of which acts as an air piston within the open end of the cylinder and
- a flexible disk air inlet valve and an air strainer located adjacent the end of the cylinder and an air jacket inclosing one end of the cylinder, said pump coöperating with the conduit for producing a blast of air through said conduit to the atmosphere before the conduit opens.
24. In a gas engine, the combination with an open end cylinder, of an explosion chamber within the cylinder, an exhaust conduit intermittently open to the chamber, and an air pump including a reciprocating power piston one side of which acts as an air piston within the open end of the cylinder and a flexible disk air inlet valve and an air strainer both carried by a cap spaced from the upper end of the cylinder and an air jacket inclosing one end of the cylinder, said pump coöperating with the conduit for producing a blast of air through said conduit to the atmosphere before the conduit opens.
25. In a gas engine, the combination with a cylinder having an ignition chamber in its wall, of a pair of power pistons concentrically mounted within the cylinder each having an ignition port in its wall adapted to open the ignition chamber to the space between the pistons, a crank shaft, and operating connections between the pistons and crank shaft.
26. In a gas engine, the combination with a cylinder having an ignition chamber in its wall, of a pair of power pistons concentrically mounted within the cylinder each having an ignition port in its wall adapted to open the ignition chamber to the space between the pistons, said ports being timed to register with the ignition chamber only at one end of the piston stroke, a crank shaft, and operating connections between the pistons and crank shaft.
27. In a gas engine, the combination with a cylinder having an intake chamber in its wall, of a pair of power pistons concentrically mounted within the cylinder each having an intake port in its wall adapted to open the intake chamber to the space between the pistons, a crank shaft, and operating connections between the pistons and crank shaft.
28. In a gas engine, the combination with a cylinder having an intake chamber in its wall, of a pair of power pistons concentrically mounted within the cylinder each having an intake port in its wall adapted to open the intake chamber to the space between the pistons, said ports being timed to register with the intake chamber only at one end of the piston stroke, a crank shaft, and operating connections between the pistons and crank shaft.
29. In a gas engine, the combination with a cylinder having an exhaust port in its wall, of a pair of power pistons concentri-

5
cally mounted within the cylinder each having an exhaust port in its wall adapted to open the cylinder exhaust port to the space between the pistons, a crank shaft, and operating connections between the pistons and crank shaft.

10
30. In a gas engine, the combination with a cylinder having an exhaust port in its wall, of a pair of power pistons concentrically mounted within the cylinder each having an exhaust port in its wall adapted to open the space between the pistons to the cylinder exhaust port said piston ports being timed to register with the cylinder port just before the pistons reach the end of their expansion stroke, a crank shaft, and operating connections between the pistons and crank shaft.

20
31. In a gas engine, the combination with a crank chamber, of a cylinder having a gas inlet chamber in its wall, of a pair of power pistons concentrically mounted within the cylinder each having a gas inlet port in its wall adapted to open the inlet chamber to the crank member, a crank shaft, and operating connections between the pistons and crank shaft.

30
32. In a gas engine, the combination with a crank chamber, of a cylinder having a gas inlet chamber in its wall, a pair of power pistons concentrically mounted within the cylinder each having a gas inlet port in its wall adapted to open the inlet chamber to the crank chamber, said ports being timed to register with the inlet chamber only at one end of the piston stroke, a crank shaft, and operating connections between the pistons and crank shaft.

40
33. In a gas engine, the combination with a crank chamber, of a cylinder having a gas inlet chamber and an intake chamber and an exhaust port and an ignition chamber in its wall the intake chamber being open to the crank chamber, a pair of power pistons concentrically mounted within the cylinder each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted to open the ignition chamber to the space between the pistons, a crank shaft, and operating connections between the pistons and crank shaft.

50
34. In a gas engine, the combination with a crank chamber, of a cylinder having a gas inlet chamber and an intake chamber and an exhaust port and an ignition chamber in its wall the intake chamber being open to the crank chamber, a pair of power pistons concentrically mounted within the cylinder

each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted to open the ignition chamber to the space between the pistons, said gas inlet ports and said ignition ports being timed to register only when the piston heads are closest together and said intake ports being timed to register only when the piston heads are farthest apart and said exhaust ports being timed to register just before the intake ports register, a crank shaft, and operating connections between the pistons and crank shaft.

80
35. In a gas engine, the combination with a casting having an inner wall forming a cylinder open at both ends and having an outer wall spaced from the cylinder and having a transverse partition dividing the space between the walls to form a cooling chamber open into one end of the cylinder, of a pair of power pistons concentrically mounted within the cylinder opposite the cooling chamber, a crank shaft, and operating connections between the pistons and crank shaft.

90
36. In a gas engine, the combination with a casting having an inner wall forming a cylinder open at both ends and having an outer wall spaced from the cylinder and having a transverse partition dividing the space between the walls to form a cooling chamber at one end of the cylinder, of an ignition chamber and a gas inlet port spaced apart and located at one side of the cylinder, a pair of intake ports and an exhaust port located in the cylinder wall and circumferentially spaced from each other and from the ignition chamber and gas inlet port, a pair of power pistons concentrically mounted within the cylinder opposite the cooling chamber and each provided with an ignition, intake and exhaust port adapted to respectively register with the ignition and intake chambers and exhaust port of the cylinder, a crank shaft, and operating connections between the pistons and crank shaft.

100
37. In a gas engine, the combination with a casting having an inner wall forming a cylinder open at both ends and having an outer wall spaced from the cylinder and having a transverse partition dividing the space between the walls to form a cooling chamber at one end of the cylinder, of a pair of power pistons concentrically mounted within the cylinder opposite the cooling chamber, a crank shaft, operating connections between the pistons and crank shaft, an exhaust conduit intermittently open to the space between the pistons, and means

coöperating with the conduit for producing a blast of air through said conduit to the atmosphere before the conduit opens, said means including one of the power pistons operating as an air piston.

38. In a gas engine, the combination with a casting having an inner wall forming a cylinder open at both ends and having an outer wall spaced from the cylinder and having a transverse partition dividing the space between the walls to form a cooling chamber at one end of the cylinder, an ignition chamber and a gas inlet port spaced apart and located at one side of the cylinder, a pair of intake ports and an exhaust port located in the cylinder wall and circumferentially spaced from each other and from the ignition chamber and gas inlet port, a pair of power pistons concentrically mounted within the cylinder opposite the cooling chamber and each provided with an ignition, intake and exhaust port adapted to respectively register with the ignition chamber, intake and exhaust ports of the cylinder, a crank shaft, operating connections between the pistons and crank shaft, an exhaust conduit intermittently open to the space between the pistons, and means coöperating with the conduit for producing a blast of air through said conduit to the atmosphere before the conduit opens, said means including one of the power pistons operating as an air piston.

39. In a gas engine, the combination with a support, of a pair of power pistons concentrically mounted in the support, a crank shaft having oppositely disposed cranks, rods directly connecting the pistons and cranks, said pistons with their respective rods being of equal weight, an exhaust conduit intermittently open to the space between the pistons, and means coöperating with the conduit for producing a blast of air through said conduit to the atmosphere during the power stroke.

40. In a gas engine, the combination with a support, of a pair of power pistons concentrically mounted in the support, a crank shaft having oppositely disposed cranks, rods directly connecting the pistons and cranks, said pistons with their respective rods being of equal weight, an exhaust conduit intermittently open to the space between the pistons and intermittently operating means coöperating with the conduit for producing a blast of air through the conduit to the atmosphere during the power stroke, said means being timed to go out of action before the conduit closes to the space between the pistons.

41. In a gas engine, the combination with a cylinder having an ignition chamber in its wall, of a pair of power pistons concentrically mounted within the cylinder each having an ignition port in its wall adapted

to open the ignition chamber to the space between the pistons, a crank shaft having oppositely disposed cranks, rods directly connecting the pistons and cranks, said pistons with their respective rods being of equal weight.

42. In a gas engine, the combination with a cylinder having an ignition chamber in its wall, of a pair of power pistons concentrically mounted within the cylinder each having an ignition port in its wall adapted to open the ignition chamber to the space between the pistons, said ports being timed to register with the ignition chamber only at one end of the piston stroke, a crank shaft having oppositely disposed cranks, rods directly connecting the pistons and cranks, said pistons with their respective rods being of equal weight.

43. In a gas engine, the combination with a cylinder having an intake chamber in its wall, of a pair of power pistons concentrically mounted within the cylinder each having an intake port in its wall adapted to open the intake chamber to the space between the pistons, a crank shaft having oppositely disposed cranks, rods directly connecting the pistons and cranks, said pistons with their respective rods being of equal weight.

44. In a gas engine, the combination with a cylinder having an intake chamber in its wall, of a pair of power pistons concentrically mounted within the cylinder each having an intake port in its wall adapted to open the intake chamber to the space between the pistons, said ports being timed to register with the intake chamber only at one end of the piston stroke, a crank shaft having oppositely disposed cranks, rods directly connecting the pistons and cranks, said pistons with their respective rods being of equal weight.

45. In a gas engine, the combination with a cylinder having an exhaust port in its wall, of a pair of power pistons concentrically mounted within the cylinder each having an exhaust port in its wall adapted to open the cylinder exhaust port to the space between the pistons, a crank shaft having oppositely disposed cranks, rods directly connecting the pistons and cranks, said pistons with their respective rods being of equal weight.

46. In a gas engine, the combination with a cylinder having an exhaust port in its wall, of a pair of power pistons concentrically mounted within the cylinder each having an exhaust port in its wall adapted to open the space between the pistons to the cylinder exhaust port said piston ports being timed to register with the cylinder port just before the pistons reach the end of their expansion stroke, a crank shaft having oppositely disposed cranks, rods directly con-

necting the pistons and cranks, said pistons with their respective rods being of equal weight.

47. In a gas engine, the combination with a crank chamber, of a cylinder having a gas inlet chamber in its wall, of a pair of power pistons concentrically mounted within the cylinder each having a gas inlet port in its wall adapted to open the inlet chamber to the crank chamber, a crank shaft having oppositely disposed cranks, rods directly connecting the pistons and cranks, said pistons with their respective rods being of equal weight.

48. In a gas engine, the combination with a crank chamber, of a cylinder having a gas inlet chamber in its wall, a pair of power pistons concentrically mounted within the cylinder each having a gas inlet port in its wall adapted to open the inlet chamber to the crank chamber, said ports being timed to register with the inlet chamber only at one end of the piston stroke, a crank shaft having oppositely disposed cranks, rods directly connecting the pistons and cranks, said pistons with their respective rods being of equal weight.

49. In a gas engine, the combination with a crank chamber, of a cylinder having a gas inlet chamber and an intake chamber and an exhaust port and an ignition chamber in its wall the intake chamber being open to the crank chamber, a pair of power pistons concentrically mounted within the cylinder each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted to open the ignition chamber to the space between the pistons, a crank shaft having oppositely disposed cranks, rods directly connecting the pistons and cranks, said pistons with their respective rods being of equal weight.

50. In a gas engine, the combination with a crank chamber, of a cylinder having a gas inlet chamber and an intake chamber and an exhaust port and an ignition chamber in its wall the intake chamber being open to the crank chamber, a pair of power pistons concentrically mounted within the cylinder each having a gas inlet port in its wall adapted to open the inlet chamber to the crank chamber and each having an intake port in its wall adapted to open the intake chamber to the space between the pistons and each having an exhaust port in its wall adapted to open the space between the pistons to the cylinder exhaust port and each having an ignition port in its wall adapted

to open the ignition chamber to the space between the pistons, said gas inlet ports and said ignition ports being timed to register only when the piston heads are closest together and said intake ports being timed to register only when the piston heads are farthest apart and said exhaust ports being timed to register just before the intake ports register, a crank shaft having oppositely disposed cranks, rods directly connecting the pistons and cranks, said pistons with their respective rods being of equal weight.

51. In a gas engine, the combination with a casting having an inner wall forming a cylinder open at both ends and having an outer wall spaced from the cylinder and having a transverse partition dividing the space between the walls to form a cooling chamber open into one end of the cylinder, of a pair of power pistons concentrically mounted within the cylinder opposite the cooling chamber, a crank shaft having oppositely disposed cranks, rods directly connecting the pistons and cranks, said pistons with their respective rods being of equal weight.

52. In a gas engine, the combination with a casting having an inner wall forming a cylinder open at both ends and having an outer wall spaced from the cylinder and having a transverse partition dividing the space between the walls to form a cooling chamber at one end of the cylinder, of an ignition chamber and a gas inlet port spaced apart and located at one side of the cylinder, a pair of intake ports and an exhaust port located in the cylinder wall and circumferentially spaced from each other and from the ignition chamber and gas inlet port, a pair of power pistons concentrically mounted within the cylinder opposite the cooling chamber and each provided with an ignition, intake and exhaust port adapted to respectively register with the ignition and intake chambers and exhaust port of the cylinder, a crank shaft having oppositely disposed cranks, rods directly connecting the pistons and cranks, said pistons with their respective rods being of equal weight.

53. In a gas engine, the combination with a casting having an inner wall forming a cylinder open at both ends and having an outer wall spaced from the cylinder and having a transverse partition dividing the space between the walls to form a cooling chamber at one end of the cylinder, of a pair of power pistons concentrically mounted within the cylinder opposite the cooling chamber, a crank shaft having oppositely disposed cranks, rods directly connecting the pistons and cranks, said pistons with their respective rods being of equal weight, an exhaust conduit intermittently open to the space between the pistons, and means co-operating with the conduit for producing a

blast of air through said conduit to the atmosphere before the conduit opens, said means including one of the power pistons operating as an air piston.

5 54. In a gas engine, the combination with a casting having an inner wall forming a cylinder open at both ends and having an outer wall spaced from the cylinder and having a transverse partition dividing the 10 space between the walls to form a cooling chamber at one end of the cylinder, an ignition chamber and a gas inlet port spaced apart and located at one side of the cylinder, a pair of intake ports and an exhaust port 15 located in the cylinder wall and circumferentially spaced from each other and from the ignition chamber and gas inlet port, a pair of power pistons concentrically mounted within the cylinder opposite the cooling 20 chamber and each provided with an ignition, intake and exhaust port adapted to respectively register with the ignition chamber, intake and exhaust port of the cylinder, a crank shaft having oppositely disposed 25 cranks, rods directly connecting the pistons and cranks, said pistons with their respective rods being of equal weight, an exhaust conduit intermittently open to the 30 space between the pistons, and means co-operating with the conduit for producing a blast of air through said conduit to the atmosphere before the conduit opens, said means including one of the power pistons operating as an air piston.

35 55. In a gas engine, the combination with a cylinder, of an exhaust pipe a cooling chamber outside said cylinder and having an outlet through the exhaust pipe to the atmosphere, and means co-operating with 40 the chamber for producing a blast of air through said chamber to the atmosphere only during the power stroke.

56. In a gas engine, the combination with a cylinder, of an exhaust pipe a cooling 45 chamber outside said cylinder and having an outlet to the exhaust pipe and means including a piston within the cylinder co-operating with the chamber for producing a blast of air through said chamber and exhaust pipe to the atmosphere only during 50 the power stroke.

57. In a gas engine, the combination with an open end cylinder, of an exhaust pipe a cooling chamber outside of and in open communication with the cylinder and having an 55 outlet to the exhaust pipe, and an air pump co-operating with the chamber for producing a blast of air through said chamber and ex-

haust pipe to the atmosphere only during the power stroke, said pump including a power piston within the cylinder one side of which acts as an air piston.

58. In a gas engine, the combination with an open end cylinder, of an exhaust pipe a cooling chamber outside of and in open communication with the cylinder and having an outlet to the exhaust pipe, and an air pump co-operating with the chamber for producing a blast of air through said chamber and exhaust pipe to the atmosphere only during the power stroke, said pump including an inlet valve adjacent the open end of the cylinder and including a power piston within the cylinder one side of which acts as an air piston. 75

59. In a gas engine, the combination with a cylinder, of a cooling chamber associated with the cylinder, an exhaust pipe and an air pump co-operating with the chamber and exhaust pipe to drive cold air therethrough only during the power stroke. 80

60. In a gas engine, the combination with a cylinder, of a cooling chamber surrounding the cylinder, an exhaust pipe and an air pump co-operating with the chamber an exhaust pipe to drive cold air therethrough only during the power stroke. 85

61. In a gas engine, the combination with a cylinder, of a cooling chamber associated with the cylinder, an exhaust pipe and an air pump co-operating with the chamber and exhaust pipe to drive cold air therethrough only during the power stroke, said air pump including a piston operating in the cylinder. 95

62. In a gas engine, the combination with a cylinder of a cooling chamber surrounding the cylinder, an exhaust pipe and an air pump co-operating with the chamber and exhaust pipe to drive cold air therethrough only during the power stroke, said air pump including a piston operating in the cylinder. 100

63. The combination with a gas engine having an internal cooling chamber, of an exhaust pipe and an air pump co-operating with the chamber and exhaust pipe to drive cold air therethrough only during the power stroke, said engine and said pump having a moving member in common. 105

In testimony whereof, I have signed my name to this specification in the presence of two subscribing witnesses.

SYDNEY I. PRESCOTT.
